W. W. WALLACE

Des. 162,910

OARLOCK

Filed Dec. 6, 1949

UNITED STATES PATENT OFFICE

162,910

OARLOCK

Waldo W. Wallace, Panama City, Fla.

Application December 6, 1949, Serial No. 6,439

Term of patent 3½ years

(Cl. D71—1)

To all whom it may concern:

Be it known that I, Waldo W. Wallace, a citizen of the United States, residing at Panama City, in the county of Bay and State of Florida, have invented a new, original, and ornamental Design for an Oar Lock, of which the following is a specification, reference being had to the accompanying drawing, forming part thereof.

Figure 1 is a view in perspective of an oar lock embodying my new design;

Figure 2 is a view in front elevation; and

Figure 3 is a view in rear elevation.

I claim:

The ornamental design for an oar lock, substantially as shown.

WALDO W. WALLACE.
